FIG. 1

INVENTOR.
WALTER G. ROEDER

BY

Walter G. Roeder
ATTORNEY

UNITED STATES PATENT OFFICE

162,990

STAND

Walter G. Roeder, Scarsdale, N. Y., assignor to The Coca-Cola Company, Wilmington, Del., a corporation of Delaware

Application October 20, 1948, Serial No. 149,195

Term of patent 14 years

(Cl. D80—10)

To all whom it may concern:

Be it known that I, Walter G. Roeder, a citizen of the United States and resident of Scarsdale, Westchester County, New York, have invented a new, original, and ornamental Design for a Stand, of which the following is a specification; reference being had to the accompanying drawing, forming a part thereof, in which

The figure is a front perspective view of a stand, showing my new design.

I claim:

The ornamental design for a stand, as shown.

WALTER G. ROEDER.
